UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

FIBER-CASE RAILWAY-TORPEDO.

1,168,936.

Specification of Letters Patent. Patented Jan. 18, 1916.

Application filed May 28, 1915. Serial No. 31,034.

To all whom it may concern:

Be it known that I, FRANK DUTCHER, a citizen of the United States, residing at Versailles, in the county of Allegheny and State of Pennsylvania, have invented certain new and useful Improvements in Fiber-Case Railway-Torpedoes, of which the following is a specification, reference being had therein to the accompanying drawing.

10 My invention relates to improvements in fiber case railway torpedoes.

The object of my invention is to provide a case having an open face in which the explosive tablet is placed, and a disk and sealing composition forming the top of the case.

Another object of my invention is to provide means whereby the rail-attaching strap is more effectively secured to the case and whereby a water-tight torpedo is produced.

20 A still further object of my invention is to provide a torpedo of this character having certain details of construction and combination of parts hereinafter more fully set forth.

25 In the accompanying drawings, Figure 1 is a perspective view of my improved torpedo. Fig. 2 is a vertical sectional view of Fig. 1. Fig. 3 is a vertical sectional view of Fig. 1 taken on the line at right angles to Fig. 2. Fig. 4 is a perspective view of the several parts forming the torpedo in their separated relation. Fig. 5 is a perspective view of a modified form of torpedo. Fig. 6 is a transverse vertical sectional view of Fig. 5. Fig. 7 is a transverse vertical sectional view of Fig. 5 taken at right angles to Fig. 6. Fig. 8 is a perspective view of the several parts forming the torpedo in their separated relation.

40 Referring now to the drawings, 1 represents the case of my torpedo which is preferably of a saucer shape and having in its bottom 4 the two slits 2 and 3. The bottom between the slits 2 and 3 is provided with 45 the downwardly pressed portion 5 forming a space through which the rail-attaching strap 6 is threaded as fully shown in Fig. 4 of the drawings.

The body portion or case 1 has a vertical 50 wall 7 and after the strap has been applied, as shown in Fig. 4 of the drawings, cement is placed on the upper face of the bottom of the case, and the disk 9 is forced down upon the cement which forces the cement

downward around the slits 2 and 3 above 55 the rail-attaching strap 6. The cement is also forced upwardly around the edges of the disk 9. A band 10 is placed around the vertical wall 7 of the case with its upper edge slightly above the upper edge of the 60 vertical wall 7. The explosive tablet 11 is then placed in the torpedo and a cement and sealing composition 12 is placed in the case on the upper face of the explosive tablet 11 and down around the oblique wall 13 65 thereof and filling the space above the explosive tablet over the upper edge of the vertical wall 7 of the case. A disk 14 is forced downwardly upon the cementing and sealing composition 12 which forces a portion 70 of the sealing or cementing composition upwardly around the edge of the disk 14 and completely seals the torpedo. By this structure and arrangement of parts it will be seen that the torpedo above and below the explosive tablet 11 is completely sealed and the band 10 prevents any spreading of the vertical wall 7 of the case. The disk 14, as heretofore described, is forced down until it rests upon the upper edge of the vertical 80 wall 7 of the case and therefore cannot be forced down a sufficient distance to force all of the cement or sealing composition from the upper face of the explosive tablet 11. The disk 14 is also approximately of a thickness 85 equal to the distance the band 10 extends above the upper edge of the vertical wall 7 of the case, and whereby the disk when in place is flush with the upper edge of the band as shown in Figs. 2 and 3. 90

In the modification shown in Figs. 5, 6, 7 and 8 instead of having the bottom 4 of the body portion 1 provided with the slits 2 and 3, I provide the bottom with an opening 15 and instead of employing a fiber disk 9, I 95 employ a metal disk 16 having an opening 17 centrally arranged. The rail-attaching clip 18 is provided with an opening 19 and a rivet 20 extends upwardly through the openings 19, 15 and 17 and is riveted upon 100 the upper face of the disk 16. This as will be understood, firmly locks the rail-attaching clip to the bottom 4 of the case 1.

Having thus fully described my invention what I claim and desire to secure by Letters 105 Patent is:

1. A railway torpedo comprising a case having an open face, an explosive tablet

within the case, a sealing composition filling the case above the explosive tablet, and a disk embedded in the sealing composition.

2. A railway torpedo comprising a case 5 having an open face, a band extending around the vertical wall of the case, an explosive tablet within the case, a sealing composition within the case above the tablet, and a disk embedded within the sealing 10 composition and resting upon the upper edge of the case flush with the upper edge of the band.

3. A railway torpedo comprising a case 15 having an open face, a rail-attaching strap secured to the case, a sealing composition in the bottom of the case, a disk embedded in said sealing composition, an explosive tablet within the case resting upon the disk, a sealing composition filling the case above the 20 explosive tablet, and a disk embedded in the sealing composition.

4. A railway torpedo comprising a case having an open face, a rail-attaching strap carried by the bottom of the case, a sealing 25 composition in the bottom of the case, an explosive tablet within the case, a sealing composition filling the case above the tablet, and a disk embedded in said sealing composition.

5. A railway torpedo comprising a case 30 having an open face, a rail-attaching strap secured to the bottom of the case, a sealing composition in the bottom of the case, a disk embedded in said sealing composition, an explosive tablet within the case and resting 35 upon the disk, a band surrounding the vertical walls of the case and extending a slight distance above the upper edge of the case, an explosive tablet within the case, a sealing composition filling the case above the explosive 40 tablet and a disk forced within said sealing composition and resting upon the upper edge of the case and having its upper edge flush with the upper edge of the band.

6. A railway torpedo comprising a case 45 having an open face, having slits in its bottom, a rail-attaching strap threaded through said slits, a sealing composition covering the upper face of the bottom of the case, a disk within the case and embedded in said sealing 50 composition, an explosive tablet within the case and resting upon the disk, a band surrounding the vertical walls of the case and extending above the upper edge thereof, a sealing composition filling the case above the explosive 55 tablet, and a disk fitting within the upper edge of the band and resting upon the upper edge of the case and having its upper face flush with the upper edge of the band.

7. A railway torpedo comprising a case 60 having an open face, an explosive compound within the case, a sealing composition filling the case above the explosive compound, and a plate embedded in the sealing composition.

8. A railway torpedo comprising a case 65

having an open face, a band extending around the vertical wall of the case and extending above the upper edge thereof, an explosive compound within the case, a sealing composition within the case above the explosive compound, and a plate embedded within the sealing composition and resting upon the upper edge of the case flush with the upper edge of the band. 70

9. A railway torpedo comprising a case 75 having an open face, a rail-attaching strap secured to the case, an explosive compound within the case, a sealing composition filling the case above the explosive compound and a plate embedded in the sealing composition. 80

10. A railway torpedo comprising a case having an open face, a rail-attaching strap secured to the bottom of the case, a band extending around the vertical wall of the case and extending above the upper edge 85 thereof, an explosive compound within the case, a sealing composition within the case above the compound, and a plate embedded within the sealing composition and resting upon the upper edge of the case flush with the upper edge of the band. 90

11. A railway torpedo comprising a case having an open face, a rail-attaching strap secured to the case, a sealing composition within the bottom of the case, a plate embedded in said sealing composition, an explosive compound within the case resting upon the plate, a sealing composition filling the case above the explosive compound, and a plate embedded within the sealing composition. 100

12. A railway torpedo comprising a case having an open face, said case having slits in its bottom, a rail-attaching strip threaded through said slits, a sealing composition covering the upper face of the bottom of the case, a plate within the case and embedded in said sealing composition, an explosive compound within the case and resting upon the plate, a band surrounding the vertical walls of the case and extending above the upper edge thereof, a sealing composition filling the case above the explosive compound, and a plate fitting within the upper edge of the band and resting upon the upper edge of the case and having its upper face flush with the upper edge of the band. 105 115

13. A railway torpedo, comprising a case having an open face, a band around the vertical wall of the case and extending above the same, an explosive tablet within the case, and a disk above the explosive tablet and flush with the upper edge of the band, and means for securing the disk in the case. 120

14. A railway torpedo comprising a case having an open face, a band extending around the vertical wall of the case and extending above the upper edge thereof, an explosive tablet within the case, a disk upon 125 130

the upper edge of the case flush with the upper edge of the band and means for securing the disk in said position.

15. A railway torpedo comprising a case having an open face, said case having a ledge around the same below the open face, an explosive tablet within the case, a sealing composition within the case above the tablet, and a disk embedded within the sealing

composition and resting upon the ledge of 10 the case flush with the upper edge thereof.

In testimony whereof I hereunto affix my signature in the presence of two witnesses.

FRANK DUTCHER.
